HANGER ATTACHMENT FOR DOOR HINGES

Allan R. Hunt, Lethbridge, Alberta, Canada, assignor of twenty-five per cent to George T. Featherston, Montreal, Quebec, Canada, and twenty-five per cent to David H. Fair, Lacolle, Quebec, Canada

Application January 10, 1947, Serial No. 721,256

1 Claim. (Cl. 248—290)

1

This invention relates to a garment supporting hook adapted to be mounted on a door hinge and secured in place by the hinge pintle.

A particular object of this invention is to provide a garment supporting hook with a transversely curved base plate adapted to embrace the cylindrical knuckles of a door hinge and a hook-retaining means engageable with the hinge pintle for securing said hook in place.

A further object is to provide an inexpensive garment supporting hook which is readily adaptable to a door hinge.

Other objects, advantages and characteristic features of the invention will be more readily understood from the following detailed description taken in connection with the accompanying drawings, in which—

Fig. 1 is a side elevational view of the garment supporting hook mounted on a hinge shown in section.

Fig. 2 is a top plan view of the garment supporting hook.

Fig. 3 is an end elevational view of the hook as it appears on the door hinge.

Referring more particularly to the drawings, 5 designates a door hinge comprising flange plates 6 and a plurality of intermeshed knuckle portions 7 adapted to receive a hinge pintle 8. The flange plates are secured to a door frame 9 and a door 10 by suitable screws 11.

A hook 12 comprising a bill portion 13 and a base plate 14 is adapted to be mounted on said door hinge. Base plate 14 is transversely curved to fit snugly against the cylindrical knuckle portions 7 of the hinge with the marginal side edges 15 of the base plate 14 being sufficiently spaced apart from hinge flange plates 6 to permit adequate opening of the door 10 with respect to door frame 9. The upper end of hook base 14 is provided with a disc-like cap portion 16 having a central opening 17. The cap portion 16 is fitted on the free end edge of uppermost knuckle 7

2

with base plate 14 embracing the cylindrical surfaces of knuckles 7. Hinge pintle 8 is then passed downwardly through the opening 17 of cap portion 16 and through the centrally aligned openings provided in the knuckles 7. The hinge pintle 8 is provided with a knob 18 so that the cap portion 16 of hook base plate 14 is secured in place between knob 18 and the uppermost hinge knuckle 7.

10 I claim:

A garment supporting hook adapted to be mounted on a door hinge comprising an elongated base plate transversely curved to fit snugly against the cylindrical knuckle portions of the hinge, a

15 disc-like cap member integrally connected to the elongated base plate at the upper marginal edge, said cap member being provided with a central opening and adapted to be fitted on the free end edge of the uppermost hinge knuckle with the

20 elongated base plate extending downwardly therefrom a substantial distance in embracing engagement with the knuckle portion of the hinge, and a bill hook having its lower end integrally connected to said elongated base plate above but in

25 close proximity to the lower end of the base plate and having its free upper end disposed below the upper marginal edge of the base plate in spaced relation thereto, the hook opposing surface of the base plate extending above the lower 30 end of the hook being free of obstructions.

ALLAN R. HUNT.
